INVENTOR

Gustavus A. Gessner,
By his Attorneys
Baldwin, Hopkins & Payton,

UNITED STATES PATENT OFFICE.

GUSTAVUS A. GESSNER, OF FREMONT, OHIO.

BOTTLE-STOPPING MECHANISM.

SPECIFICATION forming part of Letters Patent No. 368,711, dated August 23, 1887.

Application filed May 21, 1886. Serial No. 202,890. (No model.)

To all whom it may concern:

Be it known that I, GUSTAVUS A. GESSNER, of Fremont, in the county of Sandusky and State of Ohio, have invented certain new and useful Bottle-Stopping Mechanism, of which the following is a specification, reference being had to the accompanying drawings.

The object of my invention is to provide an improved stopper mechanism of that class adapted to be applied generally to jars and bottles as ordinarily made, with a lip or annular flange or projection around the top of the neck at the mouth of the bottle, so that the lip in all cases shall serve as a stop or bearing to resist or counteract the force applied to press the stopper down to place for sealing the bottle. I provide, as has heretofore been done by the use of this class of bottle-stoppers, for forcing the cap or stopper down to place in or over the mouth of the bottle perpendicularly without rotating it. I thus avoid injury to the rubber or packing, which, it is well understood, is liable to occur from rotary motion of the cap or stopper upon it while being forced to place.

In the accompanying drawings, illustrating my invention, Figure 1 is a side view of a bottle-neck with my invention applied. Fig. 2 is an opposite side view of the same. Fig. 3 is another side view, partly in section, at right angles to those of Figs. 1 and 2. Fig. 4 is a view showing the rotary ring in section and with a formal modification. Fig. 5 is a plan view of the rotary ring detached.

Referring to the letters upon the drawings, A indicates an ordinary jar or bottle having the usual annular lip, flange, or projection, B, around the mouth of its neck.

C indicates a loose or rotary ring, made of a piece of metal bent and united at its ends, fitting around the neck beneath and bearing by its upper edge against the lip B, and provided with thumb-lugs D, or the like, for turning it. The lower edge of this rotary ring is inclined or shaped so as to constitute a cam-surface. This rotary cam-ring flares or inclines outwardly at its lower edge away from the bottle-neck—*i.e.*, the lower portion of the ring has a larger internal diameter than the main body of the ring—and is provided with a hole, I, on one side, a notch, K, on the other side, and a depression, K', above the notch.

The cap or stopper G is provided with two rigid arms or lugs, L and L', on opposite sides, each of which has a hook, M M', at its lower end. One of these rigid arms L forms, by its hook M, a peculiar pivotal and sliding connection with the cam-ring, and the other arm, L', with its hook M', serves merely as a sliding catch. From this construction it will be seen that the cap can be tipped up when the cam-ring is in position for unstopping the bottle, as illustrated in Fig. 3. The hook M of arm L in that case passes into the hole I in the cam-ring, the hook and hole thus forming a hinge-joint. When the bottle is to be stopped, the cap is turned down, as shown in Fig. 2, and the hook M' of arm L' will enter the notch K. Then, owing to the outward flaring of the lower part of the cam-ring, the ring can be turned so as to bring the hooks M and M' under its incline or lower cam-edge, which will draw down the cap and accomplish the stopping or sealing of the jar or bottle, as shown in Figs. 1 and 2. Instead of having a regular outward incline or flare, the cam-ring might, with the same effect, be of angular form on its lower side in cross-section, as shown in Fig. 4.

My bottle-stopping attachment may be cheaply made by stamping the parts out of sheet metal. It will not interfere with the cleansing and refilling of all kinds of jars and bottles, and obviates all of the ordinary objections against corks and other common bottle-stopping appliances. The parts can be manufactured separately of regular sizes, so that in case one part should give out it can be cheaply supplied from the factory, thus avoiding throwing away the other part. I thus provide an improved bottle-stopping mechanism adapted to be attached permanently to all classes of bottles and jars of different sizes of the ordinary simple construction having lips around their mouths. Any suitable packing to effect a seal can be placed in the cap.

After bottles have been sealed for long periods or subjected to different temperatures, the sealing is liable to become imperfect, and the contents thus get exposed to outside air and spoil. With my appliances it is easy at any time, by turning the cam-ring farther in the direction for sealing, to close down the stopper tighter without turning it, and thus

avoid damage to the contents. By turning the cam-ring in the opposite direction slightly vent can be given, if desired.

Having thus described my improvement, 5 what I claim to be new, and desire to secure by Letters Patent of the United States, is—

1. In a bottle-stopping device, a ring having a lower portion of larger internal diameter than the main body of the ring, and having cam-surfaces on such lower portion, substantially as set forth.

2. A bottle-stopping device comprising a ring having a lower portion of larger internal diameter than the main body of the ring, and 15 having cam-surfaces on such lower portion, and a cap having arms engaging with the cam-

surfaces of the ring, substantially as set forth.

3. A bottle-stopping device comprising a ring having a lower portion of larger internal diameter than the main body of the ring, and 20 having cam-surfaces on such lower portion, and provided with a hole, I, on one side and notch K and depression K' on the other side, in combination with a cap, G, having arms L L', with hooks M M', that engage with the ring, 25 substantially as set forth.

In testimony whereof I have hereunto subscribed my name.

GUSTAVUS A. GEESNER.
